BRADFORD T. BORDEN, OF LAKEWOOD, OHIO, ASSIGNOR OF ONE-HALF TO THE BORDEN COMPANY, OF WARREN, OHIO, A CORPORATION OF OHIO, AND ONE-HALF TO WILLIAM A. NERACHER, OF WARREN, OHIO

PIPE GUIDE FOR DIESOCKS

Application filed September 18, 1930. Serial No. 482,760.

This invention relates to adjustable guides for die stocks and similar tools adapted to act on pipes of several sizes. Die stocks of this character having for instance, adjustable chasers settable for cutting several sizes of pipe require pipe guides or work holders correspondingly variable for different pipe sizes. To avoid the cumbersomeness of interchangeable bushings to be loosened and removed from the die stock, my invention provides an adjustable pipe guide mounted on the die stock and settable for different sizes of pipe. This guide comprises a pair of blocks having notches of varying depth and mounted individually on opposite sides of the pipe axis, so that different pairs of notches can be brought into position to produce different pipe openings by giving the blocks partial rotations.

It is the object of the present invention to provide such blocks in the form whereby they may be very easily changed from one size to another and at the same time when set, will be rigidly held in position. The means by which I accomplish this will be herein-after more fully explained with a description of the preferred embodiment illustrated in the drawings.

In the drawings, Fig. 1 is a face view of my pipe guide mounted on a die stock; Fig. 2 is a view of the opposite face of the die stock showing by way of illustration my arrangement for adjusting the chasers; Fig. 3 is an edge view of the die stock equipped with my pipe guide; Fig. 4 is a longitudinal central section through the die stock in a plane parallel with Fig. 3; Fig. 5 is a detail in cross section through the pipe guide itself and is indicated by the line 5-5 on Fig. 1.

As shown in the drawings, 10 indicates a suitable frame of a die stock. This carries on one end suitable threading devices to be hereinafter described, and on the other end my pipe guide. For the latter purpose, the frame is formed with an outwardly extending flat rectangular portion 11 bounded on opposite sides by outwardly projecting parallel ribs 12, thus producing a wide shallow outwardly facing channel 13 within which

the two blocks for the pipe guide are mounted.

20 and 20 indicate two blocks which cooperate with each other and the recesses to form my guide. Each of these blocks is square in maximum boundary but each face is recessed by notches designated 21, 22, 23 and 24. These notches are of successively increasing depth. The dimension across the block 20 is only slightly less than the width of the guide channel 13, so that when the block is seated within the channel, it is effectively held by the side ribs 12.

Each block 20 is held to the die stock frame by a pin 25 shown as passing through a central hole in the block and screwing into the mid-region of the flattened portion 11. This pin has a head 26 which occupies a recess 27 in the block and somewhat larger than the pin, this recess extending from the outer face to a point near the inner face of the block. There is thus an annular space around the pin between the head of the screw and the inner portion of the block which embraces the screw. In this space is mounted a helical compression spring 29 which serves to retain the block normally against the plate 11 of the die stock so that each block is held within the channel 13 and locked against rotation by the ribs 12.

It will be readily seen that to change the blocks 20 for different sizes of pipe, it is only necessary for the operator to grasp a block with his fingers engaging a pair of opposite recesses therein, pull the blocks outwardly a slight distance against the action of the spring 29 and then give the block a partial rotation, that is to say, a quarter or half turn in one direction or the other, as may be required to bring a new notch into cooperation with the other block. By this means any pair of notches may be selected in the two blocks and caused to occupy cooperating positions on opposite sides of the pipe axis and centralized therewith.

It is very convenient to make adjustable die stocks for four sizes of pipe as such adjustment meets a large number of practical requirements, thus a comparatively small die stock may be made for the size of $1/4''$, $3/8''$, 100

$\frac{1}{2}$ " and $\frac{3}{4}$ " pipe, or a larger size die stock may be made for the next set of sizes namely 1", $1\frac{1}{4}$ ", $1\frac{1}{2}$ " and 2". My adjustable guide is adapted for either of such die stocks by

5 reason of the square blocks that readily provide four different sizes of guides, which, as stated, may be selected and set with the greatest of ease and rapidity.

Any suitable form of pipe threading members may be mounted on the die stock to operate with my pipe guide. I have shown herein simply by way of illustration, the form shown and claimed in my copending application No. 447,212 filed April 25th, 1930.

10 15 As shown in that application I have provided on the end of the die stock frame, suitable radial housings made by pairs of opposed outwardly projecting lugs 15 and 16. Between these lugs are mounted radial chasers

20 30 Each chaser is provided with cutting teeth 31 on its opposite ends. Projecting from the chaser nearer one end than the other is an outwardly extending pin 32.

Secured to some of the housing lugs of the die stock frame, is an annular clamping plate 35 which, by overlying the lugs, holds the chasers therein against longitudinal movement. This clamping plate is shown as provided with three notches 36, 37 and 38 of different depth. Any notch may cooperate with a pin 32 of the corresponding chaser. To hold the clamping plate in any of its different positions and allow it to be readily shifted, it is convenient to make arcuate slots 39 in the plate and extend through these slots clamping screws 40 which are threaded in a pair of diametrically opposite housing lugs 16. By shoving the chasers inward to carry the pins 32 out of whatever notches they occupy, and by loosening the clamping screws, the annular plate may be readjusted to present different notches in line with the chasers so that they may then be brought back into a different radial position with the pins abutting the outer ends of the notches. When so adjusted, the chasers may be clamped by the tightening of the screws 40.

Though only three notches 36, 37 and 38 are shown in the clamping plate in Fig. 2, it will be observed that by reason of the double ended chasers, and the fact that the pins are nearer one end of the chasers than the other, that I can accomplish four sizes of pipe by this arrangement, for instance, with the 55 chaser turned to bring the end which is more distant from the pin inwardly and a separate chaser for the smallest size pipe, when the chaser pin occupies the notch 36 and with the next size pipe when the chaser occupies the notch 37, then by turning the chaser end for end I may set the die stock for the third size pipe with the pin occupying the same intermediate notch 37, and for the fourth or largest size pipe with the pin occupying the 60 third notch 38.

The complete die stock illustrated in the drawings is an extremely simple tool, one single integral casting forming the frame of the die stock, the frame of the pipe guide and the guides for the chasers. It is only necessary then to equip such frame on one side of the chasers with suitable clamping means and on the other with my guiding blocks and their holding springs and screws. It should be understood however, that my guide, though preferably having its frame integral with the die stock frame, may be made separate therefrom and suitably screwed thereto. Of course my guide is not limited to any particular form of holding and positioning mechanism for the chasers.

I claim:

1. The combination with a frame having an opening for the passage of a pipe, a pair of blocks having non-circular exteriors and the frame being provided with fixed means to engage such exteriors and hold the blocks in any one of several positions, said blocks having notches of different depth in their periphery, selected ones of which may register with the pipe opening, and means for permanently holding the blocks to the frame while allowing their movement to present different notches.

2. A pipe guide comprising a frame having a pipe opening, a pair of blocks pivotally mounted on the frame on axes on opposite sides of the pipe axis, said blocks having non-circular exteriors, and non-concentric ribs on the frame adapted to engage portions of such exteriors for normally holding the blocks against rotation, said blocks having peripheral notches of different depth, so that different notches in the two blocks may be brought into cooperative registration with the pipe opening of the frame, and means for pivotally securing the blocks to the frame while allowing their axial movement for a greater distance than the height of the ribs.

3. A pipe guide comprising a frame, a pair of parallel edge flanges, a pair of blocks substantially square in extreme external dimensions but recessed in each face, said blocks being adapted to be held between the flanges with any selected recess of one block adjacent that of the other block, the different recesses in the block being of different depth, said blocks being permanently pivoted at their centers but movable axially to clear the edge flanges.

4. In a die stock, the combination of a frame, a pair of blocks having notches in their periphery, a pair of pins for pivoting said blocks to the frame, each pin having a head occupying a recess on the outer face of the block which does not extend completely through the block, and a compression spring within the recess surrounding the pin between its head and the base of the recess, and means for holding the block in any one of a

number of positions when it is pressed inwardly by the spring.

5. In a device of the character described, the combination of a frame having a pipe opening and a flat rectangular portion, a pair of outwardly facing ribs at the edge of the rectangular portion, a pair of blocks having square boundaries pivotally mounted within the channel provided by the flat portion and 10 ribs, the distance across said blocks being slightly less than the width of the channel, each block being pivoted by a pin extending through its center into the channel, a compression spring surrounding the pin and held 15 by a head on the pin whereby the spring normally retains the block against the base of the channel and thus holds the block in fixed position but allows the block to be drawn outwardly further than the ribs at the edge of 20 the channel, whereby the block may be rotated and repositioned, each block having in its edge recesses of several depths, whereby a combined recess corresponding to several sizes of pipe may be obtained.

25. 6. The combination of an annular frame having a pipe opening, threading means carried by the frame on one side, a flat rectangular portion forming an integral part of the frame on the other side and extending transversely of the opening, a pair of outwardly facing ribs formed integrally with the rectangular portion at opposite edges thereof to provide a shallow outwardly facing channel, a pair of blocks materially thicker than 30 the height of the ribs and having square boundaries pivotally mounted within the channel, the distance across said blocks being slightly less than the width of the channel, each block being pivoted by a pin extending 35 through its center into the channel, a compression spring surrounding the pin and held in a recess in the block with sufficient play to allow the block to clear the ribs, whereby the 40 spring normally retains the block against the base of the channel and thus holds the block in fixed position but allows the block to be drawn outwardly further than the ribs at the edge of the channel, whereby the block may be rotated and repositioned, each block having 45 in its edge arcuate recesses of several 50 depths.

7. In a pipe guide, the combination with a suitable frame, of a pair of blocks mounted on opposite sides of the pipe axis and having 55 notches of different depth in their periphery, shoulders on the frame for locking said blocks in any one of a plurality of active positions, and spring means tending to hold the blocks in engagement with the shoulders but allowing 60 them to be withdrawn therefrom and turned to another position.

8. In a die stock, the combination of a frame, a pair of blocks having notches in 65 their periphery, a pair of pins carried by the frame for pivoting said blocks to the frame,

each pin having a head, a pair of springs respectively between such head and the corresponding block, the springs and pins co-operating with the blocks to hold them normally against the frame but allowing them 70 to be drawn outwardly by compressing the springs, and fixed shoulders on the frame adapted to overlap the blocks and engage them in any one of a number of positions when the blocks are pressed inwardly by the 75 springs but clearing the blocks when the latter are drawn outwardly to the extent allowed by the heads on the pins.

In testimony whereof, I hereunto affix my signature. 80
